UNITED STATES PATENT OFFICE

JOHN E. CORNELL, OF CHICAGO, ILLINOIS, ASSIGNOR, BY MESNE ASSIGNMENTS, TO
ST. REGIS PAPER COMPANY, OF NEW YORK, N. Y., A CORPORATION OF NEW YORK

APPARATUS FOR SEWING BAGS

Application filed January 24, 1927. Serial No. 162,956.

One object of my invention is to provide mechanism by which a bag may be fed to a sewing machine in proper relation to be sewed thereby.

5 A further object of my invention is to provide apparatus by which first one end of a bag and then the other may be sewed automatically and with the seam in exactly the preferred relation to the ends of the bag.

10 In the accompanying drawings forming a part of this specification, Figure 1 is a plan view of one form of apparatus embodying my invention; Fig. 2 is a side elevation of the apparatus shown in Fig. 1; Figs. 3 and 4 are 15 details of an aligning device; and Fig. 5 is a diagrammatic view illustrating the operation of the apparatus.

In the form of apparatus shown, there is a table 10 having parallel grooves 11 and 12 in 20 the upper surface thereof, and belts or chains 13 and 14 are mounted to run in these grooves. The chains carry pushers 15 at spaced intervals therewith.

25 Adjacent one side of the path of these pushers there is a sewing machine 16 of any suitable construction and a cutter 17 adjacent thereto.

At another point, and on the other side of the path of the pushers, there is a sewing machine 18 with an accompanying cutter 19.

30 The two sewing machines are connected by a belt or chain 20 which connects the drive shafts 21 and 22 of the respective sewing machines. If desired, the brackets carrying the 35 sewing machines and cutters may be adjustable towards or from the pathway of the pushers.

35 Approximately opposite the first sewing head there is a righthand aligner 25, shown in detail in Figs. 3 and 4. A bracket plate 26 is mounted upon the table for adjustment towards and from the path of the pushers. Plate 26 carries an upright pin 27 upon which there is pivotally mounted an arm 28 which 40 carries an aligning plate 29. A coil spring 30 mounted about pin 27 normally urges the bracket in a direction to carry the aligning plate towards the sewing machine until a heel 45 28 on arm 28 encounters an adjustable stop screw 31.

A similar aligning plate 32 is mounted upon the lefthand side of the pathway of the pushers a little in advance of the second sewing machine.

The operation of the apparatus is substantially as follows:

A bag 33 may be placed upon the table in advance of a guard plate 34 which covers the endless conveyor at the front end thereof. A bag so placed rests upon the table until 55 encountered by one of the pushers 15. It will be readily understood that the slight friction of the bag upon the table is sufficient to cause it to rest snugly against the pusher throughout its length, so that the axis of the 60 bag is exactly perpendicular to the line of travel of the pusher. When the right end of the bag encounters the righthand aligner, the bag is automatically moved endwise until it 65 abuts a stop plate 35 in connection with the 70 lefthand sewing machine, which brings it into proper position to have its left end closed by the lefthand sewing machine. In the construction shown, the sewing machine is adapted to apply a tape 36 to the seam as 75 it is sewed. While a bag end is being sewed by the lefthand sewing machine, the tape is cut between it and the preceding bag by the cutter 17, and immediately after the bag 80 passes the lefthand cutter the left end of the 85 bag encounters the left aligner, whereupon the bag is shoved to the right until it encounters a suitable stop plate 37 in connection with the righthand sewing machine. This places the bag in proper position to have 90 its right end closed by the righthand sewing machine.

It is detrimental to have a bag pushed by a pusher while the needle is in the fabric. In order to avoid this, each sewing head is supplied with the usual intermittent feed device, and this device is set to operate at a speed slightly faster than that of the pusher. No harm results from the intermittent feed device feeding a trifle more rapidly than the 95 pusher, as the abutment plate keeps the bag in line and prevents any material retardation of the end of the bag away from the sewing machine. Therefore, the feed device is normally set to feed sufficiently faster than the 100

pusher so that unavoidable variations will not slow it up to a speed less than that of the pusher.

It is highly desirable to have both ends of the bag closed at the same operation, so that but one operator is required for closing both ends of the bag. If two sewing machines are placed opposite each other and an attempt is made to feed the bag between the sewing machines so as to sew both ends at one time, difficulty is encountered where the bag is of paper, and especially where reinforced seams are to be applied to paper bags having valves.

One of the sources of difficulty is the practical impossibility of feeding the two ends of the bag in absolute unison. Of course, the sewing machines are provided with the ordinary feed dogs, as stated above, in order to move the bags between stitches in the customary manner, and any slight difference in the rate of feed of the two sewing machines is likely to be much more detrimental in sewing paper than in sewing cloth or similar material, because the cloth will readily yield and allow one end to be fed more rapidly than the other.

The practical impossibility of maintaining an equal rate of feed in the two sewing machines lies partly in the difficulty of timing the machines in exact unison and arranging the feed dogs so that their travel above the plate is exactly equal, and also in the difficulty of maintaining the two feed dogs so that they are equally sharp and will grip the paper at the two ends of the bag to the same extent. Even were it possible to maintain absolute equality between the two feeding devices, there are sometimes differences in the glaze of the paper, or other features involved in the seizing of the paper by the feed dogs, so that absolute equality of feed by the two machines at the two ends of the bag would be very difficult to maintain.

Another difficulty is in maintaining absolutely equal lengths in successive bags. This difficulty is especially marked where multi-wall bags are used, but also applies to other bags. It will be readily seen that slight differences in the lengths of successive bags will result in differences in the depths of the seams, where the sewing machines are placed opposite each other. This is particularly detrimental where a valve is formed by tucking in one corner of a bag, as a seam of the proper depth is essential in forming a valve of proper size to receive a feed tube and also of proper proportions to close correctly after the bag has been filled. Furthermore, the seam must be deep enough to avoid tearing out, and too great depth results in a waste of material.

By the construction shown, it will be seen that slight variations in the speed of feed of the two sewing machines are immaterial, and that the depth of the seam is not affected by slight variations in the lengths of the bags,

as the end of the bag is always shoved over to a fixed position in relation to the sewing machine which is operating thereon.

While I have shown one form of mechanism for carrying out my invention, it will be understood that various changes may be made within the scope of the appended claims.

What is claimed is:

1. In a bag sewing machine, a table, a pusher adapted to engage one edge of a bag on the table, means to move the pusher in a straight line over the table, a sewing machine at one side of the path of the pusher, a stop having a face parallel with the direction of movement of the pusher, and means to move a bag endwise against the stop while it is being moved by the pusher and in advance of its reaching the sewing machine.

2. In a bag sewing machine, a table, a pusher adapted to engage one edge of a bag on the table, means to move the pusher in a straight line over the table, a sewing machine at one side of the path of the pusher, a stop plate having a face parallel with the direction of movement of the pusher and on the same side of the path of the pusher as the sewing machine, and an aligner on the opposite side of the path of the pusher from the sewing machine and adapted to move a bag endwise against the stop plate.

3. In a bag sewing machine, a table, a pusher adapted to engage one edge of a bag on the table, means to move the pusher in a straight line over the table, a sewing machine at one side of the path of the pusher, a stop plate having a face parallel with the direction of movement of the pusher and on the same side of the path of the pusher as the sewing machine, and an aligning plate inclined to the path of the pusher and on the opposite side of the path of the pusher from the stop plate, and yielding means tending to move the aligner towards the stop plate.

4. In a bag sewing apparatus, a table, a groove in the top of said table, an endless member running in said groove, a pusher at right angles to the groove and attached to said member, a sewing machine at one side of the groove, a stop plate on the same side of the groove with the sewing machine and having a face parallel with the groove, and means on the other side of the groove adapted to move a bag into abutting relation with said stop plate as the bag is being pushed over the table by the pusher.

5. In a bag sewing machine, a table, a pusher, means to move the pusher in a straight line over the table, a sewing machine at one side of the path of the pusher, a stop plate having a face parallel with the direction of movement of the pusher and on the same side of the path of the pusher as the sewing machine, means to move a bag endwise against the stop plate while it is being moved by the pusher and in advance of its reaching the sew-

ing machine, and feeding means connected with the sewing machine and adapted to feed material to be sewed at least as rapidly as the pusher is moved.

5 6. In a bag sewing machine, a table, a sewing machine having feeding means forming a part thereof, a stop plate at one side of the sewing machine and having a face parallel with the direction of said feeding means, and
10 automatic means adapted to feed a bag to the feeding means of the sewing machine with one end abutting the stop plate.

15 7. In apparatus for sewing bags, a sewing machine adapted to sew reinforcing tape to the end of a bag, means to move the end of the bag through the sewing machine, means to sever the tape and seam after the bag has passed through the sewing machine, a second sewing machine, and automatic means for
20 moving the bag endwise after the tape is cut to position its other end in position to be closed by said second sewing machine.

25 8. In apparatus for sewing bags, a sewing machine adapted to sew reinforcing tape to the end of a bag, means to move the end of the bag through the sewing machine, means to sever the tape and seam after the bag has passed through the sewing machine, means for moving the bag, after the tape has been
30 severed, in a line parallel with the reinforced seam, a second sewing machine substantially in line with the other end of the bag and adapted to sew a seam across said other end, a stop for the end of the bag in line with said second
35 sewing machine, and a guide in position to engage the first sewed end and press the bag endwise against said stop after said tape has been cut and while the last said means is moving the bag to said second sewing machine.

40 40. In testimony whereof, I have hereunto signed my name to this specification.

JOHN E. CORNELL.
